GOVERNOR MECHANISM FOR PNEUMATIC MUSICAL APPARATUS.

1,165,081.

Specification of Letters Patent.

Patented Dec. 21, 1915.

Application filed May 8, 1913. Serial No. 766,279.

To all whom it may concern:

Be it known that we, JOHN P. EUSTIS and ALBERT T. BROWN, both citizens of the United States of America, residing, respectively, at Newton, county of Middlesex, and State of Massachusetts, and Arlington, county of Middlesex, and State of Massachusetts, have invented certain new and useful Improvements in Governor Mechanism 10 for Pneumatic Musical Apparatus, of which the following is a specification.

This invention relates to governor mechanism for controlling the motors of pneumatic musical apparatus, and whereby the 15 tempo of the piece of music to be produced may be varied. Incidentally thereto, the invention relates to the means for stopping the motor and means for producing the rewind of the perforated music sheet.

20 Among the objects of the present invention are, first: the arranging of the parts so that they shall be compact and occupy as little space as possible; second: the improvement of the valve mechanism, including the 25 valve seats so that the mechanism will be sensitive to the atmospheric tension produced therein; third: the construction of the various chambers of the apparatus of metal, such as high brass; fourth: the provision of 30 absolutely leak-tight joints; and fifth, the increased efficiency and durability of the parts of the apparatus. These being among the objects of the present invention, the same 35 consists of certain features of construction and combinations of parts to be hereinafter described and then claimed with reference to the accompanying drawings illustrating a suitable embodiment of the invention, and in which—

40 Figure 1 is a sectional front elevation of so much of the mechanism as is requisite for illustrating the present invention; Fig. 2 is a sectional plan in which the motor is omitted; Fig. 3 is a longitudinal section on the line 45 3—3, Fig. 1, showing more particularly the governor box; Fig. 4 is a detail transverse section on the line 4—4, Fig. 3; Fig. 5 is a detail longitudinal section on the line 5—5, Fig. 1; Fig. 6 is a vertical section on the 50 line 6—6, Fig. 1; Fig. 7 is a transverse section on the line 7—7, Fig. 1; Fig. 8 is a transverse section on the line 8—8, Fig. 1; Fig. 9 is an end view of a portion of the mechanism illustrated in Fig. 1 as viewed from the right

of said figure, and Fig. 10 is a detail perspective view of a valve guide member.

Referring to Fig. 1, a portion of the well-known pneumatic motor 1 is illustrated, the same being supported by a standard 2 and a suction pipe 3. The pipe 3 is, by means of an 55 elbow 4, connected with the trunk pipe 5 of the motor. In the present invention the governor box 6 is arranged underneath the motor and is provided at its inner end with a socket 7 which receives the lower end of the 60 motor standard 2, which is secured by a set screw 8. The suction pipe 3 has at its lower end an elbow 9 which is inserted within an annular flange 10 surrounding an opening 11, the connection being air tight. A suction 65 pipe 12 is connected with the pumping bellows (not shown) and is provided with an upturned end 12^a, the upper end of which is inserted in an opening in the lower or fixed 70 board of governor pneumatic 13. The movable board or leaf of the said pneumatic carries an automatic cut-off or regulator 14 for controlling the tension produced in said 75 pneumatic.

Governor pneumatic 13 connects by means 80 of a pipe 15 with a metallic valve box 16 arranged below the governor box 6 which is also metallic, and said valve box provides a chamber 16^a, and at one end is provided with an opening 16^b in its bottom. A hollow metallic shell 17 arranged between the valve box 16 and the governor box 6 provides an intermediate chamber 18, said shell being provided with side flanges 17^a which are secured air-tight to the bottom of the 85 governor box 6. Tempo slide rod 19 is arranged and guided in said governor box 6 and is adapted to adjust a valve such as 20 in a well-known manner. Preferably the underside of the slide valve 20 is provided with a 90 felt facing 20^a, and said valve is connected with the rod 19 as by means of a coupling device 21 which may be of any suitable construction.

At the respective ends of the governor box 100 6 are metallic bushings 22, 23, in which the slide rod 19 is guided. The bottom of the metallic governor box 6 is provided with an elongated valve controlled opening 24 extending in the direction of movement of the 105 tempo rod 19, and the said valve opening is so formed and constructed as to provide for nicety of fit and tempo control. To this end

the said valve opening 24 is drifted directly into the metal of the governor box bottom, and is smaller at one end than at the other, its smaller end corresponding to a slow time and its larger end to a quick time movement of the motor, and hence the perforated sheet of music (see Fig. 3). The said valve opening tapers from its smaller end toward its larger end, there being a gradual taper 24^a 5 from its smaller end for a considerable portion of the length of the valve opening or slot, and the wider portion of the opening or slot 24^b being of marked wideness as compared with the narrower portion 24^a, and 10 the said portions 24^a and 24^b being connected by a more abruptly tapered portion 24^c. Obviously the narrower portion 24^a of the valve opening provides for a more gradual accelerated movement of the motor, while the 15 wide portion 24^b provides for a more or less sudden accelerated and increased movement of the motor. It will be seen that the construction is such that the felt facing of the valve 20 seats flush upon the metallic edges 20 surrounding the valve opening 24, and obviously these edges can be ground and rounded off so as to reduce any burning or vibratory noises such as whistling, which might otherwise occur. The ends of the 25 governor box 6 are sealed air-tight by means of metallic disks or caps 25, provided with inturned flanges 26 which are fitted snugly into the ends of said box.

Shell 17 before mentioned is provided at 30 one end, preferably just beyond the enlarged end of the valve controlled opening 24, with a downwardly extending neck 27 Figs. 1 and 7, surrounding an opening or port 28 and inserted into an opening in the top of the 35 valve box, with which box the pipe 15 communicates. The said opening or port 28 is under the control of a valve 30 which is provided with a valve stem 31, which may be actuated in a well-known manner by the difference in the tension on opposite sides of a 40 diaphragm 32, so as to open or close said valve against valve seat 29 formed by the protruding end of the neck 27. Said diaphragm 32 is arranged in a chamber 33 which is formed by two concave or bulging metallic shells 34 and 35, which clamp and 45 secure the edge of said diaphragm in air-tight manner. Located above the chamber 33 and within the chamber 16^a of box 16 50 which is formed by two concave or bulging metallic shells 34 and 35, which clamp and secure the edge of said diaphragm in air-tight manner. Located above the chamber 33 and within the chamber 16^a of box 16 55 which is formed by two concave or bulging metallic shells 34 and 35, which clamp and secure the edge of said diaphragm in air-tight manner. Located above the chamber 33 and within the chamber 16^a of box 16 60 which is formed by two concave or bulging metallic shells 34 and 35, which clamp and secure the edge of said diaphragm in air-tight manner. Located above the chamber 33 and within the chamber 16^a of box 16 65 which is formed by two concave or bulging metallic shells 34 and 35, which clamp and secure the edge of said diaphragm in air-tight manner. The box 41 is closed at one end by means of an end cap 54 provided with a flange 54^b which is set into and secured in said box 16^a.

tends from the shell 34, which neck is inserted in an opening 16^b in box 16. The shoulders or abutments 38 will spring under the inner end of the neck 39 and the shoulders or abutments 37^a will spring in contact with the outer end of said neck, whereby the guide member consisting of sleeve 36 and its arms will be securely held in central position for guiding the valve stem 31.

A tube 40 preferably of metal leads from 75 a well 40^a struck up from the bottom of the diaphragm chamber 33 to the outer air in a well-known manner. The means for controlling the admission of air at atmospheric pressure to the said tube 40 need not be 80 shown as it is so well-known, it being usually controlled by a valve operated by a push-button, adapted when pressed to stop the motor.

Box 16 before mentioned and another metallic box 41, are arranged transversely of the governor box 6 and underneath the same, the box 41 being located to the right of the box 16 and adapted when short-circuited to the bellows to rewind the music sheet 90 quickly. (See Figs. 1, 5 and 6.) The said box 41 forms a chamber 41^a, and said box is further provided with an opening 41^b in its bottom. Suction pipe 12 passes through the opposite walls of the metallic box 41 and is 95 provided with a side opening 42 for establishing direct connection between the said pipe and the chamber 41^a.

At the openings in the walls of box 41 through which said pipe 12 passes, are outwardly extending flanges 43 which surround the said pipe 12 and are secured thereto in air-tight manner. For the purpose of securing the box 41 to the governor box 6, the latter is provided with an opening into 105 which is inserted a neck 44 extending from said box 41 and surrounding a valve opening or port 45, the end of said neck being sufficiently projected or protruded to form a valve seat 46.

A valve 47 is adapted to work against said seat 46 and open or close as desired said port 45, and said valve is provided with a valve stem 48 which is guided in a guide member 49 which is in all substantial respects similar to the guide member 36, 37 before described. Guide member 49 is sprung into opening 41^b referred to. It will be seen that the valve 30 works toward the governor box 6 to close its port, while the valve 47 works in a direction away from said box to close its port. The stem of valve 47 is operatively connected with flexible diaphragm 50 located in chamber 51 formed by two concave or bulging metallic shells 52 and 53, between the edges of which the said diaphragm is secured in air-tight manner. The box 41 is closed at one end by means of an end cap 54 provided with a flange 54^b which is set into and secured in said box 16^a.

end, said cap being in all substantial respects similar to the end cap 54^a of valve box 16. At the other end of the metallic box 41 is a transparent pane 55 which is secured 5 between an inner flanged ring 56 and an outer ring 57, the said pane being secured in the box in an air-tight manner by means of said two rings. At the front end of the valve box 16 are rings 56^a and 57^a between which 10 is confined in air-tight manner a transparent pane 55^a, said parts being substantially identical with the front end of the box 41.

A rewind valve 57^a is provided which is mounted on an arm 58 carried by a rock-shaft 59, mounted on supporting bracket 60 which is carried by the supply-pipe 12, said valve serving to close valve orifice or port 61 in a well 62 at the bottom of the chamber 51. Said rock-shaft 59 is operated in a well-known manner for the purpose of enabling 20 the rewind of the music sheet to be performed by the apparatus. Extending from the well 62 is a tube 63 which is connected with an exhaust apparatus, so that the same 25 tension of rarefied air is produced at opposite sides of the diaphragm 50.

On one end of the governor box 6 is located a relief valve 64 and this is well-known. At the opposite end of the governor 30 box over a top opening 65 therein, is secured a transparent pane 66 by means of frames 67 to which the said pane is secured in air-tight manner. Other transparent panes can be mounted in the apparatus and 35 secured in air-tight manner and be held in the same way by frames which are secured to the supporting member by means of screws so that the said panes can be removed for the purpose of obtaining access to any internal 40 part which the observer finds is not working correctly. All of the joints in the apparatus are made air-tight and the metallic parts are made air-tight by solder or brazing.

The general operation of this sort of apparatus is well understood. Briefly described it is as follows: In playing a piece of music, the motor 1 is driven through the medium of air exhausted therefrom and 50 which flows from the motor, through pipe 3, into the governor box 6, through the valve aperture 24, which may be throttled more or less by the valve 20, through the chamber 18, into valve box 16, through pipe 15, into the 55 governor pneumatic 13 and through the suction pipe 12, which is connected with the air exhaust apparatus. Obviously, the motor will be stopped when atmospheric air is admitted through tube 40, which thereby raises 60 the diaphragm 32, as the air tension will then be greater on that side of the diaphragm than on the valve side, whereupon the valve 30 closes its port. The reversing gear (not shown) is then actuated so as to 65 change the direction of movement of the

music sheet and the motor, and the low tension air supplied through pipe 12 will be short-circuited in the following order: Through the pipe 3, the corresponding end of the governor box 6, through port 45 and 70 through opening 41 in the pipe 12. Of course, in order to establish this short-circuit, the rewind valve 57 must be opened to atmospheric pressure, whereby the valve 47 is moved from its seat. The described parts 75 are located above the wind-chest, indicated in Fig. 1.

Obviously this invention is susceptible of modification, as parts may be omitted, parts added, and parts substituted without departing from the spirit and scope thereof.

What we claim as new is:—

1. In governor mechanism for pneumatic musical apparatus, the combination of air chambers, valve means between said chambers for effectuating a gradually accelerated movement of the motor, and for effectuating relatively to such accelerated movement a more suddenly proportioned and less gradually accelerated and increased movement, 85 one of said air chambers containing a slide valve and another a plunger valve, and an elongated shell, at the top and bottom of which the seats for said valves are respectively located.

2. In governor mechanism for pneumatic musical apparatus, a metallic governor box provided in one wall with an elongated valve orifice extending longitudinally thereof, an elongated metallic shell covering said orifice, means for supplying a tension through said orifice and shell, and a slide-valve controlling said orifice to vary said tension.

3. In governor mechanism for pneumatic 105 musical apparatus, a metallic governor box having a lateral valve seat and comprising a hollow elongated tubular portion and metallic end caps, each having a stiffening flange inserted and secured air-tight in the 110 end of said tubular portion.

4. In governor mechanism for pneumatic musical apparatus, a governor box having a lateral valve seat and comprising a hollow tubular portion and end caps, each having a 115 stiffening flange joined air tight with the end of said tubular portion.

5. In governor mechanism for pneumatic musical apparatus, a metallic governor box having a lateral valve seat and comprising 120 a hollow tubular portion and end caps, each having a flange inserted and secured air-tight in the end of said tubular portion, aligned guide bushings held in the said end caps, and a slide rod guided in said bushings 125 and carrying a valve for controlling the opening within said seat.

6. In governor mechanism for pneumatic musical apparatus, a governor box provided with a valve-controlled orifice, a valve box, 130

a valve therein, a chamber intermediate of said boxes, one wall of which has a neck-surrounded orifice, said neck being inserted air-tight into said valve box, and a valve seat for said valve formed by the protruding edge of said neck.

7. In governor mechanism for pneumatic musical apparatus, a governor box provided with a valve controlled orifice, a metallic valve box, a valve therein, a chamber intermediate of said boxes and provided with metallic walls, the latter having a neck-surrounded orifice, said neck being inserted air-tight into said valve box, and a valve-seat for said valve, formed by the protruding edge of said neck.

8. In governor mechanism for pneumatic musical apparatus, a governor box provided with a valve-controlled orifice, a valve box, a valve therein, a chamber intermediate of said boxes and having a neck-surrounded orifice, said neck being connected air-tight with said valve box, and a valve seat for said valve formed by the protruding edge of said neck.

9. In governor mechanism for pneumatic musical apparatus, a governor box provided with a valve controlled orifice, a valve box, a valve therein, a chamber intermediate of said boxes and having a neck-surrounded orifice, said neck being of metal and inserted air tight into said valve box, and a valve-seat for said valve, formed by the protruding edge of said neck.

10. In apparatus of the character described, the combination of a governor box, a valve box communicating therewith to one side thereof and having an opening on that side remote from said governor box, a guide fitted into said opening friction tight, and a valve provided with a stem guided in said guide and adapted to control the communication between said two boxes.

11. In apparatus of the character described, the combination of a sheet metal box, a tension pipe extending through openings in said box and having an opening communicating with the interior of said box, and flanges struck up from said box, at said openings thereof, and surrounding and forming air-tight connection with said pipe.

12. In governor mechanism for pneumatic musical apparatus, the combination of a governor box, a box having a neck inserted into an opening in said governor box and forming an air-tight connection, the end of said neck providing a valve seat, and a pneumatically controlled valve for acting against said seat.

13. In governor mechanism for pneumatic musical apparatus, the combination of a governor box, a metallic box having a neck inserted into an opening in said box and forming an air-tight connection, the end of said

neck providing a valve-seat, and a pneumatically controlled valve for acting against said seat.

14. In governor mechanism for pneumatic musical apparatus, the combination of a governor box, boxes arranged transversely thereof and connected therewith, means for supplying tension through all of said boxes, and valves for controlling the connection of said transverse boxes with said governor box.

15. In governor mechanism for pneumatic musical apparatus, the combination of a metallic governor box, metallic boxes arranged transversely thereof and connected therewith, means for supplying tension through all said boxes, and valves for controlling the connection of said transverse boxes with said governor box.

16. In apparatus of the character described, the combination of a wind-chest, a motor located above said wind-chest, a tempo governor separate from said wind-chest, and comprising a governor box, a pneumatic, and valves associated with said box and pneumatic, all of the said parts of said governor being located above said wind-chest, between it and said motor, the said valves of said governor being disassociated from said wind-chest, and means for supporting said governor and said motor in said positions.

17. In apparatus of the character described, the combination of a horizontal wind-chest, a motor located above said wind-chest, a tempo governor separate from said wind-chest and comprising a governor box parallel with said wind-chest, a pneumatic arranged horizontally on top of said governor box, and valves associated with said box and pneumatic, all of the said parts of said governor being located above said wind-chest, between it and said motor, the said valves of said governor being disassociated from said wind-chest, and means for supporting said governor and said motor in said positions.

18. In apparatus of the character described, the combination of a governor box, a governor pneumatic exterior to said box, valved connections between said box and pneumatic but extraneous to said box, conducting means extraneous to said box for exhausting air from said pneumatic, and a separate valve outside of said valved connections and operated by said pneumatic for opening or closing the connection between said extraneous conducting means and said pneumatic.

19. In apparatus of the character described, the combination of a motor, a governor box, a governor pneumatic exterior to said box, valved connections between said box, pneumatic and motor, a conduit from said pneumatic and which is extraneous to

said box, a valve operated by said pneumatic for opening or closing the connection between said conducting means and pneumatic, and a direct valve controlled connection between said conduit and motor when the first said valved connections are rendered neutral.

5 20. In apparatus of the character described, the combination of a governor box, an exhaust pipe adjacent to it, a bracket on 10 said pipe, a rotary valve shaft journaled

in said bracket, a valve for said box controlling a passage to said pipe, a diaphragm chamber the diaphragm of which operates said valve, and a valve operated by said shaft to admit atmospheric air past the same to move said diaphragm.
